UNITED STATES PATENT OFFICE

GEORGE DEAN, OF ARMTHORPE, NEAR DONCASTER, AND HENRY AINSLEY, OF SEASCALE, ENGLAND; SAID AINSLEY ASSIGNOR TO SAID DEAN

LIQUID-SUPPLY SYSTEM

Application filed July 23, 1927, Serial No. 208,004, and in Great Britain July 30, 1926.

This invention relates to the selective supply of various liquids, as, for instance, different brands of lubricating oils, or of liquid fuels or the like, and it has for its object 5 to provide simple and effective apparatus for this purpose, so that liquid from any one of a number of separately stored different kinds may be quickly and easily obtained as required.

10 According to this invention, there is employed to control admission of the liquid into the pump or like measuring vessel a cut-off valve (or more than one) which is adapted when closed to fill any clearance existing be- 15 tween the walls of the vessel and the piston therein.

It will be understood that by the term "clearance" is meant such space or spaces within the container as are not swept by the latter's piston during the stroke by which the liquid is discharged. It will be seen, therefore, that the invention provides for the complete emptying of the pump or like measuring vessel, so that inaccuracy in the quantity de- 25 livered through clearance spaces in the pump is entirely avoided, and their mutual contamination is prevented.

In the accompanying drawings—

Figure 1 is an elevation of an apparatus 30 for the supply of various liquids constructed in accordance with this invention, showing the pump barrel and control valve mechanism in section;

Figure 2 is a plan view of Figure 1, to a 35 larger scale, partly in section showing one of the control valves opened;

Figure 3 is a section on the line III—III of Figure 1 showing the disposition of the conduits from the various liquid containers;

40 Figure 4 is a sectional view of a modified pump and control valves;

Figures 5, 6, and 7, respectively, are fragmentary sectional views of pumps showing further alternative constructions of control 45 valves;

Figure 8 shows in section a modified piston formed in two relatively movable parts;

Figure 9 being a further development thereof.

50 In carrying out the invention, a preferred

arrangement illustrated in Figures 1-3 is to employ a single pump 2 which may be mounted centrally on a base 3 or if preferred within a container divided by partitions into compartments each adapted to hold a different liquid. Thus any convenient number of compartments may be provided around the pump, or they may be at a distance from it and connected to it by the conduits 4.

An important feature of the pump is that the piston 5 or plunger employed is adapted to make close contact with the end wall or cover or head 6 of the working end of the cylinder 7. If desired, means on the plunger or end wall would be employed to make the contact forcibly, so that the liquid therein may be completely expelled from the cylinder. Also means are provided for closing or blocking off the clearance spaces created by the inlet and outlet passages from the pump.

Connecting the pump 2 with the interior of each liquid compartment is a suction pipe 4 jointed to the end cover 6 of the pump and controlled by an inlet valve (not shown) which may be a ball in a valve chamber at 70 the foot of the pipe 4 or at an intermediate part thereof. The suction pipe 4 communicates with the interior of the pump 2 through a port 8 in the end cover 6 within which is a seating for a cut-off valve. This latter is a 75 conical plug 9 so shaped that when closed down on the seating it fills exactly the port 8 level with the inner end of the cover 6 of the cylinder. Thus, when this valve 9 (which

may be actuated by means projecting out of the end wall of the cylinder, such as the lever 10, which is attached to a guided extension 11 of the cut-off valve 9 so that movement of the lever in one direction withdraws the valve from its seating) is closed, the whole of the clearance space due to the port 8 is filled, whilst the contact of the piston 5 with the end 6 of the cylinder 7 eliminates all clearance there also. Any desired number of valves controlling the suction pipes to the 85 pump may be spaced around the cover 6.

In Figure 2 a portion of the piston is shown cut away, thus exposing the end wall of the cylinder and also showing the outline of the ports as they appear when the valves 100

are closed. The end of the delivery valve is also seen and the remaining portion around the valves 9 is in section.

In Figure 4 is shown a modification of the 5 cut-off valve illustrated in Figures 1-3. Here the valve is a cylindrical plug 25 having its axis inclined to the cylinder bore, and its inner end 26 is bevelled accordingly to lie, when seated, level with the inner surface of 10 the cover 6. It may be operated by a lever 10 as previously described.

A modification of the valve is shown in Figure 5. In this the valve 27 is of the disc type having holes 28 and 29 to permit the escape 15 of any liquid trapped before the valve actually closes. To uncover the port 8 it moves axially, its actuating means being the screw 30 or other means having similar function.

A further modification and arrangement 20 of this valve is shown in Figure 8. The axis of this valve 31 is inclined to the cylinder bore and the inner end 32 is shaped so as to conform to the part-spherical ended piston 5 when the valve is seated.

25 In Figure 7 a cut-off valve 35, broadly similar to that in Figure 4, has its axis at right angles to the pump axis. It enters the side of the pump, and part of the bevelled portion 36 seats on a correspondingly bevelled surface 37 of the pump cylinder 7, whilst the other part is level with a conical ended surface at the end of the pump. The piston has a conical lower end fitting accurately the conical end surface of the pump.

35 Obviously, the valves which fill and close the ports are so arranged that liquid trapped in may escape before the valve actually seats, and many types of valve may be used.

The foregoing constructions permit of providing 40 the pump with one or more integral or detachable heads or covers having, at spaced intervals around them, connections for each of the various liquid compartments, and each connection may include a suction 45 and delivery valve and a cut-off valve to isolate these valves from the pump.

With any of the arrangements illustrated, the delivery valve 19 from the pump can be arranged centrally in the end wall or head 50 6 and may be of any preferred kind such as is shown in Figure 1, in which a plug 20 having at one end a conical portion seating in the end wall of the cylinder, whilst the other end has an axial recess communicating 55 by lateral passages with the annular space formed between the valve when lifted and its seating. A spring 21 normally keeps the valve on its seating, although if preferred positive seating means may be employed.

60 With this type of valve, the discharge of liquid from the pump is greatly facilitated. Alternatively, a ball type delivery valve as illustrated in Figure 4 may be used, in which the ball 22 is normally kept against its seat 65 23 by a spring 24.

Operation of the pump in Figure 1 is direct, the piston 5 being reciprocated by means of a rack-and-pinion mechanism (not shown). The pinion is carried on a shaft operable by the handle 45, and an adjustable stop 46 limits the travel of the piston 5 so that measured quantities of liquids may be withdrawn. To maintain atmospheric pressure on the top side of the piston a vent is provided at 47 in a casing enclosing the 70 rack. The piston 5 may be provided with scraper rings 48 so as to ensure complete discharge from the pump.

In Figure 4 there is no direct mechanical action upon the pump 2. Suction and pressure are applied to the piston 5 alternately by any known means through a port 49 in the top of the pump cylinder.

A valve 50 is fitted to the piston 5, and remains open during suction, thus facilitating exit of air from under the piston. When the liquid reaches the piston 5 the valve 50 closes and an extension 51 operated by this valve protrudes from the top of the cylinder to form an indicating device. At the end of the delivery stroke the valve 50 opens and any liquid left in or adhering to the delivery valve is completely expelled.

As a further means for withdrawing air during suction from the underside of the piston, and more particularly when a working fluid is used in the top portion of the cylinder, a modified form of dual piston, such as is illustrated in Figure 8, is used. In this construction the piston is in two parts 52 and 53 and the valve 50 has a seating in the lower portion 53. When working fluid is drawn from the top of the cylinder 7 the suction thus created causes the piston 52, 53 to rise and open the valve 50, and any air below the piston is accommodated in the space 54 between the two piston parts 52 and 53, the valve 50 closing when the liquid from the container reaches it.

By returning to the top of the cylinder the withdrawn working fluid, the contents below the piston are discharged and the valve 50 again opens. Thus the expulsion of the contents 54 scavenges the delivery valve.

If, when operating the pump, the amount of air in the pipes 4 exceeds the capacity of the space 54 between the two piston parts 52, 53, or should the suction in this space be insufficient to withdraw all the air from under the piston 53 and so allow the liquid to reach the lower surface thereof and close the valve 50, these difficulties may be overcome by a slight modification of the piston and associated parts.

Such an arrangement is shown in Figure 9, in which a dual piston 64, 65 is provided with a valve 66 (corresponding to the valve 50 in Figure 8) in the lower portion 65, and the latter has a stem 67 which extends slidably into a hollow part 68 of the upper por-

tion 64 of the piston. The valve 66 has a hollow body containing a ball inlet valve 69 and a similar discharge valve 70, controlling the space 71 between the two piston parts, and this body is slideable axially in the stem 67 which is made hollow at 72 for this purpose.

When operating this pump, if, as above mentioned, the air in the pipes 4 is in excess of the capacity of the space 71 between the two pistons, then the upper piston part 64 is returned to the lower part 65, and in so doing the contents of the space 71 are discharged through the ball valve 70, and thereafter the part 64 is raised and any remaining air is drawn through the valve 69 from beneath the piston. These movements may be repeated until the incoming liquid from the containers reaches the lower piston part 65 and thereby closes the valve 66, when a full measure will be drawn into the pump.

By these means the necessity for discharging partial quantities of liquid previous to making a further suction stroke is obviated and ensures a correct measure being obtained before any discharge from the pump takes place.

As a further means to prevent premature discharge of liquid through the delivery valve 73 during reciprocation of the piston part 64, a lever such as 74 pivoted at 75 bears at one end on the valve 73 and keeps it upon its seating until the correct measure is drawn into the pump and is thereafter released during the delivery stroke.

As before, the closing of the valve 66 may operate an indicating device, showing that a full charge has been drawn into the pump.

A further arrangement is to slide the upper piston inside the lower piston, i. e., a piston within a piston. With any type of dual piston, the upper portion can be operated mechanically if desired, as by means of a rack-and-pinion.

It will be seen, therefore, that with apparatus of this kind any liquid can be readily supplied on demand, and the pump and its clearance spaces can be so effectively emptied or isolated that there is no risk of objectionable contamination of two or more different liquids.

Alternatively, any mixture of liquids can be obtained by opening the necessary combination of cut-off valves. Where a definite mixture of liquids is desired the opening of the cut-off valves may be graduated for this purpose.

These pumps may be so modified that liquids may be fed to the pump vessels and/or delivered therefrom by pressure, gravity, or suction.

As an alternative to the foregoing arrangements, a separate pump may be provided for each liquid, with the axes of their plungers arranged either radially or cylindrically in a circle, or grouped, so that a centrally mounted

lever or other mechanical device could be employed selectively to engage with each pump, or any other reciprocating mechanism might be employed instead of the lever.

As a further alternative, instead of a mechanical operation for the separate pumps, they could be operated by fluid pressure developed in a central pump from which branch passages, selectively operable at will, could convey the pressure to the pump controlling the desired kind of liquid.

The invention provides for the neat storage and distribution of a number of brands of liquids, and, as the pumps in each case may be adapted to supply any measured quantities, the necessity for separate measuring apparatus for each liquid is avoided.

What we claim as our invention and desire to secure by Letters Patent of the United States is:—

1. In a liquid supply system, the combination of a pump provided with a piston which completely fills the clearance space within its cylinder, a head for the pump provided with a plurality of separate conduits adapted to be connected to containers for various liquids, said head containing a plurality of cut off valves adapted to control the conduits in which each cut-off valve is in the form of a plug, movable in a direction axially with respect to its seating, which seating is around the conduit at the latter's junction with the pump wall, and the part of the valve exposed to the interior of the pump is shaped to conform to the surface of the pump wall.

2. In a liquid supply system, the combination of a number of separate conduits adapted to be connected to containers for various liquids, a pump provided with a piston which completely fills the clearance space within its cylinder, means in the head of the cylinder adapted to control the withdrawal of the predetermined liquid, comprising a radially arranged conical cut-off valve adapted when closed to fill any clearance existing between the wall of the vessel and the piston therein.

In testimony whereof we have signed our names to this specification.

GEORGE DEAN.

HENRY AINSLEY.
